Neil Gray

UNITED STATES PATENT OFFICE.

CHARLES HAMMER, OF HOLLIS COURT BOULEVARD, NEW YORK.

COMBINED LUG CAP AND LINER PLATE.

Application filed August 22, 1925. Serial No. 51,728.

To all whom it may concern:

Be it known that I, CHARLES HAMMER, a citizen of the United States, residing at Hollis Court Boulevard, in the county of 5 Queens and State of New York, have invented certain new and useful Improvements in Combined Lug Caps and Liner Plates, of which the following is a specification.

10 This invention relates to a combined cap or closure and sealing member or liner plate for containers, such as glass containers, the primary object of the invention being to provide a combined cap or closure and improved self-centering re-usable liner plate therefor, so constructed that a material saving in the metal of the liner plate and the material of the gasket is obtained, and which will be properly retained in the cap against 15 premature separation therefrom during the application of the cap to the container, and which will effectively permit the release of the liner plate from the container when the same is vacuum-sealed without the mutilation or injury of the liner plate or its gasket, so that the same can be readily re-used, and which is also so constructed as to properly center itself on the container.

20 A further object of the invention is the provision of an improved metal sealing member or liner plate, particularly applicable for use with rotary metal caps having inwardly extending lugs or projections and which can be instantly released from 25 the container without injury or destruction of the gasket on the removal of the cap.

25 In practice, the closure or cap has to be made of a diameter which will permit the depending flange or skirt thereof to overlap the projections or threads on the container. In other words, the diameter of the skirt of the cap has to be sufficiently large to permit this skirt to pass over the projections or threads of the container. To make the 30 liner plate of this diameter means the loss of a considerable amount of material or metal in the making of millions of liner plates, and also loss of a material amount of gasket material, and therefore the primary 35 object of the present invention is to provide a self-centering liner plate which may be made of considerably less diameter than that of the cap skirt but which nevertheless will be maintained in position during the application of the cap to the container by the holding lugs or projections of the cap, and

which thus enables a comparatively narrow thin gasket to be used, so that there is a material saving in the quantity of gasket material, and which can be easily released from 60 the container without injury or destruction of the gasket, so that the liner plate can be effectively re-used, and which moreover will permit the cap to be readily rotated into place or released without interfering with 65 the position of the liner plate, and its gasket, relative to the sealing surface of the container.

70 In the drawings accompanying and forming a part of this specification, Fig. 1 illustrates one form of rotary cap partly in section which may be used together with the improved liner plate or sealing member applied to a glass container; Fig. 2 is an enlarged detail view of the cap and sealing member shown in Fig. 1; Fig. 3 is a perspective view of this improved liner plate or sealing member; and Fig. 4 illustrates the liner plate in position on a glass container after removal of the cap, the dotted 75 lines illustrating the manner in which an instrument, such as a knife blade, may be readily inserted at the lower edge of the skirt of the liner plate, so as to release the 80 gasket from the container.

85 Similar characters of reference indicate corresponding parts in the several views.

Before explaining in detail the present improvement and mode of operation thereof, I desire to have it understood that the invention is not limited to the details of construction and arrangement of parts which are illustrated in the accompanying drawings, since the invention is capable of other 90 embodiments, and that the phraseology 95 which I employ is for the purpose of description and not of limitation.

The cap or closure in the form shown, is what is now commonly known in the trade as an Amerseal cap, it comprising a top 100 2 having a depending flange 3 provided with a curled or strengthened or beaded lower edge 4 commonly termed a "wire edge", and which skirt has suitable knurls or corrugations 5, the curled edge being provided 105 with lugs or projections 6 adapted to engage suitable projections or threads 7 of a glass container when the cap is rotated on to the container.

110 The liner plate may be used, however, with a ring formed cap in which case the liner plate itself would form the top of the cap.

Located within this rotary cap is this improved sealing member or liner plate 8, which comprises a disk or plate 9 wholly enclosed by the cap when the form of cap 5 shown is used. And this plate is provided with an annular recess 10 for the reception of a flat ring gasket 11, which gasket is relatively narrow and comparatively thin. This liner plate is provided with a depending 10 flange 12 of shallow formation, it being but little deeper than the thickness of the gasket, which as stated, is comparatively thin and narrow, and this flange flares outwardly, the lower edge 12' of this liner plate flange 12 15 having a diameter greater than the diameter between the lugs of the cap whereby, when the cap is in position to be applied to a container, the lower edge 12' of this outwardly flaring flange 12 will rest upon the lugs of 20 the cap and thus be prevented from falling out of the cap during the application of the cap to the container.

The top of this flaring flange however, as at 12" has a diameter no greater and usually less than the diameter between the lugs, whereby a considerable quantity of metal is saved in the manufacture of these caps, since the top of the liner plate may be made of materially less diameter than the interior 30 diameter of the cap skirt, and the lower edge of the flange of the liner plate need only be made of sufficient diameter to have it rest upon the lugs of the cap and prevent its premature displacement.

35 By an inspection of Fig. 2 it will be seen that the skirt or flange of the cap at 13 must have a diameter sufficiently large to overlap the threads 7 of the glass container, and consequently if the liner plate is of this 40 size, a greater quantity of material must be used in the manufacture of each plate so that in the manufacture of millions of these plates, there is a great loss of material, not only in the metal of the liner plate, but 45 in the gasket material which has to be used, since the gasket has to be wider as the outer edge has to engage the flange of the liner plate, while the inner portion thereof has to rest upon the top of the container, but 50 by flaring the depending flange of the liner plate outwardly as shown in Fig. 2, in which the depending flange has a cylindrical portion for the reception of the gasket and below the gasket an outwardly flaring portion, the top of the liner plate need only 55 be made of a diameter sufficient to correspond with the top of the container while the lower edge of the flange of the plate, by reason of this flare, will be in position 60 to contact with the lugs of the cap and thus be prevented from premature displacement during the application of the cap to the container, for it will be obvious that in the handling of millions of these caps at the 65 rate of many thousands per day, if the

liner plate during the application of the cap to the container should fall therefrom, a great loss of time would result in the operator picking up the plates and replacing them in the cap.

Furthermore, by making the depending flange of the liner plate of shallow formation and but slightly deeper than the thickness of the gasket or ring fitting therein, a knife blade can be readily inserted after 75 the removal of the cap or closure from the container between the lower edge of the liner plate and the top of the container to permit the access of air and thus release the vacuum and so permit the ready removal 80 of the liner plate from the container.

Thus, the construction of the present improved liner plate accomplishes several important objects: It permits a knife blade to be readily inserted between the flaring portion of the flange and the container and by using the container thread as a fulcrum the gasket can be easily pried sufficiently to release the vacuum and permit its ready removal; it prevents the premature displacement 90 of the liner plate in the cap; the shallow depending flange facilitates the centering of the liner plate on the mouth of the jar or container, since the flange extends slightly below the gasket, especially where 95 the containers are not true to form, but are slightly oval, whereas if the flange of the liner plate were straight and made of considerably less diameter than the cap, the result would be that the lower edge of the 100 flange of the liner plate would strike the top of the container mouth, but by the flared construction of the liner plate, the flange of the liner plate, even though the container should be slightly oval in form, 105 in other words out of true, will pass over the outer wall of the mouth of the container, and thus center the liner plate, so that this flared construction of the liner plate flange enables the liner plate to be made much 110 smaller in diameter, yet without interfering with the centering of the liner plate on the container, even though the latter may not be true to form; it saves a material amount of metal in the formation of the liner plate 115 and a material amount of gasket material, since the latter can be made of considerably less width as well as somewhat thinner.

In consequence, the present improved construction of liner plate having the shallow flaring depending flange conserves the amount of metal required in the formation thereof, and in the amount of gasket material, insures the proper centering of the liner plate upon the container regardless of 120 whether the container is true to form or not, and prevents the premature separation of the liner plate from the cap during the handling thereof, while at the same time permitting 125 the effective use of a suitable instru- 130

ment to release its sealing contact with the container mouth edge.

It is to be understood that by describing in detail herein any particular form, structure or arrangement, it is not intended to limit the invention beyond the terms of the several claims or the requirements of the prior art.

Having thus explained the nature of my 10 said invention and described a way of constructing and using the same, although without attempting to set forth all of the forms in which it may be made, or all the modes of its use, I claim:

15 1. A combined cap and liner plate, each having a depending flange, the flange of the cap having inwardly extending lugs or projections for securing it on to a container, a gasket carried by said liner plate, the flange 20 of the liner plate having a depth slightly in excess of the thickness of the gasket and flaring outwardly so that the diameter thereof at its lower edge is greater than that between the lugs of the cap.

25 2. A combined cap and liner plate, each having a depending flange, the flange of the cap having inwardly extending lugs or projections for securing it on to a container, a gasket carried by said plate, the flange of 30 the liner plate having a depth slightly in

excess of the thickness of the gasket and flaring outwardly, the diameter of said flaring flange at the top of the plate being no greater than that between the cap lugs, and the diameter of the lower edge of the flaring flange being greater than that between the cap lugs. 35

3. A combined cap and self-centering liner plate, each having a depending flange, the flange of the cap having inwardly extending 40 lugs or projections for securing it on to a container, a relatively narrow thin gasket carried by said plate, the flange of the liner plate having a depth slightly in excess of the thickness of the gasket and flaring outwardly, whereby the liner plate will center 45 itself upon a container and whereby the insertion of an instrument between the liner flange and the container is readily effected. to release the liner plate the diameter of 50 said flaring flange at the top of the plate being no greater than that between the cap lugs, and the diameter of the lower edge of the flaring flange being greater than that between the cap lugs, whereby the liner 55 plate will be prevented from premature separation from its cap.

Signed at Brooklyn, New York this 31st day of July 1925.

CHARLES HAMMER.
